DISPENSER TOP FOR A PRESSURIZED CONTAINER

Philip L. Crowell, Racine, Wis., assignor to S. C. Johnson & Son, Incorporated, Racine, Wis.

Filed Sept. 29, 1966, Ser. No. 4,096

Term of patent 14 years

(Cl. D58—26)

FIG. 1 is a perspective view of a dispenser top for a pressurized container illustrating my new design;

FIG. 2 is a front elevational view;

FIG. 3 is a side elevational view;

FIG. 4 is a top plan view; and

FIG. 5 is a rear elevational view.

I claim:

The ornamental design for a dispenser top for a pressurized container, as shown.
